UNITED STATES PATENT OFFICE.

DAVIS S. WILLIAMS, OF LOS ANGELES, CALIFORNIA.

REINFORCED-CONCRETE RAIL-TIE.

1,244,813.

Specification of Letters Patent. Patented Oct. 30, 1917.

Application filed January 20, 1917. Serial No. 143,422.

To all whom it may concern:

Be it known that I, DAVIS S. WILLIAMS, a citizen of the United States, residing at Los Angeles, in the county of Los Angeles and 5 State of California, have invented a new and useful Reinforced-Concrete Rail-Tie, of which the following is a specification.

This invention relates to improvements in reinforced concrete rail ties and resides in 10 the provision of a tie which will be durable, capable of easy handling and relatively inexpensive to manufacture.

An object of the invention is to provide an arrangement of reinforcing elements 15 which will prevent strains and stresses from cracking or in any way proving detrimental to the concrete body of the tie and therefore provide for the supporting of rails in perfect alignment and against spreading action.

20 Another object is to provide a rail fastening means coöperating with the reinforcing elements of the tie so as to hold the rails against creeping or spreading and provide for the ready removal or placing of the tie 25 without disturbing the positions of the rails.

Other objects and advantages will appear during the course of the following description.

The accompanying drawings illustrate 30 the invention:

Figure 1 is a top plan view of a tie constructed in accordance with my invention.

Fig. 2 is a top plan view of the reinforcing elements removed from the concrete 35 body of the tie.

Fig. 3 is a side elevation of the tie.

Fig. 4 is a side elevation of the reinforcing elements.

Fig. 5 is an end view of the tie.

40 Fig. 6 is a fragmentary longitudinal sectional view taken through the tie showing the rail clamping means in position and holding a rail upon the tie.

Fig. 7 is a transverse sectional view taken 45 on line 7-7 of Fig. 6; and

Fig. 8 is an enlarged fragmentary sectional view taken longitudinally of the tie at one end thereof.

50 Referring to the drawings, 1 designates a concrete tie body which is provided with inclined sides 2, the base of the tie being wider than the upper surface thereof. At each end the body is enlarged as at 3 and deepened as at 4 so as to provide additional 55 strength at the points where the rails are supported and an anchoring means which

will finally embed itself in the road bed. At points near its ends the body is widened transversely by outwardly projecting rail supporting portions 5 which extend from 60 opposite sides of the body and are formed integral therewith. The projections 5 together with the upper face of the body with which the upper faces of the projections are flush, provide a relatively long rail supporting 65 surface which increases the solidity and supporting efficiency of the tie.

The reinforcing elements of the tie extend both longitudinally and transversely thereof. Embedded in the tie body at the ends 70 thereof and near its lower side, are transverse tie rods 6, the ends of which terminate flush with the sides of the tie, and embedded longitudinally within the tie in a horizontal plane, are reinforcing bars 7 and 8 arranged 75 parallel to one another and adjacent to opposite sides of the tie. The ends of these bars 7 and 8 are bent up and over the tie rods 6, as shown clearly at 9 in Fig. 8 of the drawings.

80 Embedded in the tie transversely thereof above the rods 6, are tie rods 10 and 11, the rods 11 being located above the ones 10. Reinforcing bars 12 and 13 arranged in pairs, preferably, are mounted upon the 85 rods 10 and 11 respectively, and are embedded longitudinally in the tie. These bars 12 and 13 are straight and parallel to each other and the bars 7 at points intermediate the ends of the tie body, but from points 90 adjacent to the inner sides of the projections 5, are curved downwardly and then upwardly toward their free ends, at which latter points they are hooked as at 14 over the rods 10 and 11. The bars 12 and 13 together with the bars 7 and 8 provide for 95 reliable reinforcing of the concrete body and the bars 12 and 13 in being bent as described take the full shear and bending strains at any section of the tie and distribute the tensile stresses over a sufficient area of the concrete so that it will not be crushed by excessive side thrusts of the rods. Embedded in the concrete transversely thereof at points above the rods 11 at the 105 ends of the tie are tie rods 15 which have corresponding tie rods 16 located in the same planes therewith at points on the inner sides of the extensions 5. Curved reinforcing bars 17 are embedded longitudinally 110 in the tie and the ends lie on opposite sides of the extensions which are bent over the

rods 15 and 16 as at 18. These rods take up the shear strain not accounted for by the other bars.

Embedded in the enlarged portions of 5 the tie and extensions 5, longitudinally of the extensions, are reinforcing bars 19 which have their ends bent back upon themselves at 20 and located adjacent the upper corners of the extensions at the outer ends 10 thereof. These bars extend downwardly and inwardly under the bars 7 and 8 and over and upon the bars 17. Reinforcing wires 21 are embedded longitudinally and transversely in the extensions 5 and the upper wire 21 is wound around the bent back ends 20 of the bars 19. Vertical wires 22 are provided at the ends of the extensions 5 and the wires 21 are connected therewith. These wires 21 are crossed centrally of the 20 ends of the bars 19 and are so arranged that the tie is reinforced against breaking or cracking incident to accidental strains, such as might occur in piling up the ties or during transportation, and the bars 19 reinforce the extensions 5 against shear strains such as would be caused by uneven tamping.

Embedded longitudinally in the tie body and connected at their ends with the tie rods 30 6 are reinforcing wires 23 which extend over the tie rods 10, 11, 15 adjacent the upper surface of the tie for the length thereof upon the outer sides of and parallel with horizontal portions of the bars 12 and 13. 35 These wires serve to reinforce the tie against accidental strains such as defined as prevented by the wires 21. Embedded in the tie body between the extensions at the ends of the tie are transversely extending wires 40 24 surrounding and engaging the bars 7, 8, 12 and 13 which serve to hold the longitudinal reinforcing rods in position during the forming of the tie.

Formed in the tie body near the ends 45 thereof and on opposite sides of the points thereof to support rails are openings 25 which are substantially wedge shaped and adapted to receive rail-clamping means which will be later more fully described. 50 Upon their inner vertical faces the openings 25 are inwardly offset and provide shoulders 26 adapted to be engaged by lateral projections 27 on the lower ends of bolts 28. Bolts 28 are placed within the openings 25 with their 55 screw-threaded ends 29 uppermost and located out of the openings. Rail base engaging plates 30 having openings therein to receive the bolts are mounted upon the bolts and held in position by nuts 31 turned on 60 the screw-threaded ends 29. To prevent the shoulders 26 from being cracked or broken, there are provided transverse reinforcing rods 32 embedded in the concrete along the faces of the shoulders, as shown clearly in 65 Fig. 6 of the drawings. Countersinks 33 are

formed in the tie body and extensions 5 so as to receive fibrous or other similar cushion plates 34. The rails are adapted to rest upon these plates 34. The bars 32 have their lower faces exposed so that the projections 70 27 will engage therewith. Hard wood wedges 35 which are preferably creosoted are inserted in the openings 25 to hold the bolts 28 in position. These wedges are driven in firmly and on account of the resiliency thereof act to absorb side shocks from the rails and therefore prevent the chipping or cracking of the concrete at the upper outer edges of the openings 25.

The gage of the track may be regulated 80 according to the size and shape of the wedges together with the angle of inclination of the openings for the wedges and bolts. It will be seen that the rail fastening means may be readily removed and inserted 85 in a comparatively short time.

The reinforcing elements are held together as described and provide a fairly rigid frame which is placed in the mold for the tie and when embedded in the concrete 90 provides a tie which is reinforced against all possible strains and stresses and therefore will prove exceptionally durable and strong. It will be noted that the reinforcement as a whole is symmetrical to center 95 lines and that the long rail-bearing surface provided by the extensions 5 is reinforced so that breaking thereof is eliminated.

While the foregoing specification and accompanying drawings define the preferred 100 form of my invention, it is to be understood that various minor changes as to details of construction may be resorted to when required without departing from the spirit and scope of the invention as defined in the 105 subjoined claims.

I claim:

1. A rail tie comprising a concrete body portion, transverse rods embedded in the ends of the body portion, and longitudinal 110 reinforcing bars embedded in the body portion and having their ends bent over the tie rods, bars embedded in the body portion transversely and near the ends thereof, certain of said longitudinal rods being curved 115 at the points in the body portion which are adapted to support the rails and engaging with the transverse bars.

2. A rail tie comprising a concrete body, transverse tie rods embedded in the ends of 120 the body, lateral projections extending from opposite sides of the tie body at points near the ends thereof, longitudinal reinforcing bars embedded in the tie body and having their ends bent over the tie rods, reinforcing 125 bars embedded longitudinally in the projections and extending transversely through the tie body, certain of said first named reinforcing bars being straight for their entire length and the other of said reinforcing bars 130

being curved downwardly adjacent their ends and extending under and engaged with the reinforcing bars embedded longitudinally in the projections, and wire connections between said bars for holding them in the desired relation to one another.

3. A rail tie comprising a concrete body, transverse tie rods embedded in the ends of the body, lateral projections extending from opposite sides of the tie body at points near the ends thereof, longitudinal reinforcing bars embedded in the tie body and having their ends bent over the tie rods, reinforcing bars embedded longitudinally in the projections and extending transversely through the tie body, certain of said first named reinforcing bars being straight for their entire length and the other of said reinforcing bars being curved adjacent their ends, wire connections between said bars for holding them in the desired relation to one another, and reinforcing wires connected with certain of the transverse tie rods extending over said tie rods and being embedded in the tie body longitudinally thereof.

4. A reinforced concrete rail tie comprising a concrete tie body, longitudinal reinforcing rods embedded in the body, transverse tie rods embedded in the body at the

ends thereof, said longitudinal bars being hooked over the tie rods, certain of said bars being horizontal throughout their entire length and the other of said bars being curved downwardly adjacent their outer ends at points beneath the surface of the tie body which are adapted to support the rails, and curved reinforcing bars embedded in the body at the ends thereof and having their ends located on opposite sides of points adapted to support the rails.

5. A reinforced concrete rail tie comprising a concrete tie body, longitudinal reinforcing rods embedded in the body, transverse tie rods embedded in the body adjacent to the ends thereof, said longitudinal bars being secured to the tie rods, bars embedded transversely in the body at points near the ends thereof and between the tie rods and certain of said longitudinal bars being curved downwardly adjacent their ends and extended beneath and in engagement with the last named bars.

Signed at Los Angeles, California, this 10th day of January, 1917.

DAVIS S. WILLIAMS.
